FIG-3

FIG-4

FIGURE 1 is a perspective view of a combination pump and motor housing; showing my new design;

FIGURE 2 is an end elevational view thereof, looking from the left side of FIGURE 1;

FIGURE 3 is a side elevational view thereof, showing the side opposite that shown in FIGURE 1, and

FIGURE 4 is an end elevational view thereof, taken from the right side of FIGURE 1.

The broken line disclosure of a fragmentary water tank and supporting bracket in FIGURE 1 is for illustrative purposes only.

I claim:

The ornamental design for a combination pump and motor housing, substantially as shown and described.
